UNITED STATES PATENT OFFICE.

JOHN WEBER, OF PHILADELPHIA, PENNSYLVANIA.

MUSICAL INSTRUMENT.

1,347,977.

Specification of Letters Patent. Patented July 27, 1920.

Application filed April 7, 1919. Serial No. 288,395.

To all whom it may concern:

Be it known that I, JOHN WEBER, a subject of the King of Hungary, residing at Philadelphia, in the county of Philadelphia and State of Pennsylvania, have invented 5 certain new and useful Improvements in Musical Instruments, of which the following is a specification.

One object of my invention is to effect 10 the automatic playing of a number of musical instruments electrically when another musical instrument is manually played and more particularly to effect the automatic playing of musical instruments, such as 15 wind operated instruments and xylophones by the manual playing of a chromatic accordion.

Another object is to so construct my invention that various combinations of tones 20 produced in the bass or accompaniment section of the chromatic accordion can be automatically produced in the bass or accompaniment section of another wind operated instrument and at the same time to so arrange 25 the parts of my invention that the melody or chromatically arranged section of a manually operative accordion can be operated to produce the automatic operation of the melody or chromatically arranged section 30 of another wind operated instrument.

A still further object is to make my invention of a simple and durable construction so that the manually operative accordion can be manipulated without inconvenience to the 35 musician and so that the automatically operative musical instruments can be placed at positions remote from the manually operative instrument.

Another object is to so construct my invention 40 that the musician, playing upon the manually operative instrument can by various switch devices effect the stopping or operation of any of the automatically operative instruments or the stopping of various sections of the automatically operative instruments.

These objects, and other advantageous ends which will be described hereinafter, I 45 attain in the following manner, reference being had to the accompanying drawings in which—

Figure 1 is a diagrammatic view showing the general electrical connection between various musical instruments constructed in 55 accordance with my invention,

Fig. 2 is a transverse sectional elevation

of a manually operative chromatic accordion made in accordance with my invention,

Fig. 3 is an enlarged fragmentary section 60 of certain of the parts shown in Fig. 2,

Fig. 4 is a diagrammatic view showing certain of the elements in the bass and chromatically arranged key sections of the manually operative accordion shown in Figs. 2 65 and 3,

Fig. 5 is a side elevation of an electrically operative wind instrument made in accordance with my invention, the same being illustrated as made in the form of a chromatic accordion with its sections at opposite 70 sides of the bellows secured in substantially fixed relation,

Fig. 6 is an elevation of Fig. 5 looking in the direction of the arrow α , 75

Fig. 7 is a transverse sectional elevation taken on the line 7—7 of Fig. 6 and drawn on an enlarged scale,

Fig. 8 is an enlarged fragmentary section of certain of the parts shown in Figs. 5, 80 6 and 7,

Fig. 9 is a transverse sectional elevation of a xylophone arranged in accordance with my invention,

Fig. 10 is an enlarged fragmentary side 85 elevation partly in section of a portion of the xylophone shown in Fig. 9, and

Fig. 11 is a fragmentary section through a modified form of solenoid.

Referring to the drawings, 12 represents 90 a manually operative portable chromatic accordion, 13 is a wind operated instrument made out of a chromatic accordion by securing together its sections at each side of its bellows as will be described hereinafter, and 95 which can be automatically played when the accordion 12 is manually operated, and 14 represents a xylophone which also can be automatically played by the manual playing of the accordion 12. The accordion 100 12, as in the usual construction of accordions of this type, includes two general sections 15 and 16, the section 15 having the melody or chromatically arranged keys 17, and the section 16 having the accompaniment or bass keys 18. The keys 17 are arranged in layers or banks and are operatively connected to valves 19 having the usual reeds (not illustrated), in alinement therewith, said reeds being adapted to vibrate to produce the various tones when air 110 is expelled from and taken in the air cham-

ber 20, when said sections are moved apart and together to produce the air compression and suction in the usual manner of manually operative accordions; it being noted that in the accordion 12, the usual accordion plaited bellows 21 is provided between the sections 15 and 16, as clearly shown in Fig. 2.

The keys 18 in the bass or accompaniment section 16 are connected in the usual manner to various harmonic combinations of valves 22, as clearly shown in Figs. 2 and 4. Thus when any one of the keys 18 is manually moved it will serve to operate a number of the valves 22 to produce a harmonic combination of low tones which provides the obligato or accompaniment to the melody, for example, as played upon the keys 17.

The instrument 13 also includes a chromatic or melody section 23 and a bass or accompaniment section 24 which are secured together by a bar 24^a; an air chamber 25 being provided between said two sections. Keys 26 in the section 23 are operatively connected to valves 27 which are in alignment with reeds (not illustrated), which are preferably arranged to vibrate only when the valves are opened to permit escape of air from the chamber 25, said reeds serving, when the valves 27 are opened due to the automatic movement of the keys 26 in a manner hereinafter described, to vibrate and thereby produce tones caused by the escape of air from said chamber 25. Air is supplied to the chamber 25 by means of a bellows 28, said bellows being operated by connecting rods 29 on a shaft 30. The shaft 30 has a pulley wheel 31 thereon which is driven by a belt 32 connected to an electric motor 33. The bellows 28 has a flexible tube connection 34 with the chamber 25. The top section 35 of the bellows 28 has an arm 36 pivotally mounted thereon, said arm having a valve 37 which normally closes an opening 38 in the top section 35. The valve 37 is normally held in a closed position by a spring 39 which presses against the arm 36. However, if the air pressure in the bellows 28 becomes too great the end 40 of the arm 36 will strike against a stop 41 on the frame 42 and cause the valve 37 to be opened to release the pressure within the bellows. Thus the valve 37 serves as a safety valve to prevent injury to the bellows. Cushion springs 43 are interposed between the section 35 of the bellows and the top 44 of the frame 42 and serve to provide pressure to prevent the section 35 from rising too quickly and also to keep the air within the bellows under pressure.

A partition 45 is provided in the casing 46 of the instrument 13 and separates the air chamber 25 from a compartment 47, said compartment 47 being directly above the top 44 of the frame 42. Bass or accom-

paniment section valves 48 are mounted within the compartment 47 and are arranged in alignment with reeds (not illustrated) which are adapted to vibrate in the usual manner when the valves 48 are opened 70 to permit the air from the chamber 25 to escape. The valves 48 are arranged similarly to the valves 22 in the accordion 12.

The xylophone 14 comprises a frame 49 having mounted thereon vibratory tone producing bars 50, said bars, as illustrated, being arranged in horizontal position and capable, when struck, of producing musical sounds. The frame 49 is mounted on a standard 51. The accordion 12 has two 80 metallic busbars 52 and 53. The busbar 52, as clearly shown in Figs. 3 and 4, has elongated portions 52^a which extend in a serpentine or zig-zag manner between the layers or banks of keys 17. These busbars are 85 connected together by an electric wire 54 which includes a switch 55 and extends to one pole of an electric battery 56 or other suitable generator of electricity. Each of the keys 17 is provided with a metallic 90 finger 59, and springs 60 are positioned between the respective fingers 59 and the busbar 52, said springs normally being out of engagement with the busbar 52 and also serving to hold the keys 17 in their normal 95 position. However, when any of the keys are depressed, their respective fingers will move the springs 60 into engagement with the adjacent portions 52^a of the busbar 52 and thereby provide an electric connection 100 between the fingers 59 and the busbar 52. A coupling block 61 of insulating material is made in two sections 62 and 63. The section 63 of the coupling block 61 has metallic recessed members 64 which are spaced apart 105 and adapted to be engaged by metallic pins 65 in the section 62; said pins fitting within the recesses of said members 64 and serving to hold the two sections together and also to provide an electric contact between the pins 65 and the members 64. The members 64 are connected by wires 66^a to the respective fingers 59, as clearly shown in Fig. 1. Each of the pins 65 has a wire 66 connected thereto, said wires 66 being respectively connected to metallic pins 67 in a section 68 of a coupling block 69. The coupling block 69 has another section 70 constructed similarly to the section 63 of the coupling block 61, said section having recessed metallic members 71 into which the pins 67 fit. The members 71 are respectively connected by wires 72 to one end of wire coils 73 of solenoids 74. The opposite ends of the wire coils 73 are connected to a metallic busbar 75. The busbar 75 in turn is connected by a wire 76 to the opposite pole of the battery 56. The solenoids 74 have slid able metallic cores 77 which, when an electric current is passed through the 130

respective wire coils 73, will be pulled or drawn into the solenoids 74 in the manner well known in connection with solenoids. From the foregoing description it will be understood that any one of the keys 17 of the accordion 12 is manually moved, the valve 19 connected therewith will be opened to produce a tone and at the same time an electric circuit will be completed through the busbar 52 and finger 59, and the respective solenoid 74, which is connected electrically therewith, will be energized to move its core. The cores 77 have eyelets 78 (see Figs. 7 and 8) which form pivotal connections for links 79, said links being pivotally connected to arms 80. The arms 80 are pivotally connected at 81 to an extension 82 of the casing 46 of the instrument 13 and are also connected with rods 83. The rods 83 are adjustably bolted, as shown at 84, to the arms 80, and the upper ends of the rods 83 are pivotally connected to the keys 26. The keys 26 in turn are pivoted at 87. It will, therefore, be seen that when the cores 77 of the solenoids 74 are moved that they will operate the keys 26 and open the valves 27. This action will release air from the chamber 25 and cause the vibrations of the reeds and a tone will be produced corresponding to the tone produced by the opening of the corresponding valve in the accordion 12. The inner ends of the solenoid cores 77 are provided with cushioned tips 88 which are adapted to strike the upper ends of adjusting screws 89 which are mounted within said solenoids. It will be noted that by turning the adjusting screws 89 the extent of inward movement of the cores 77 will be varied and therefore the extent of the opening movement of the valves 27 will be varied. Thus it is possible to regulate, by the use of the screws 89, the volume or character of tone emitted from the instrument 13 when the valves 27 are opened. It will be further noted that the rods 83 also provide adjustment which will change the position of the cores 77 with relation to the keys 26 and thereby vary the tone produced by the opening of the valves 27.

The bass or accompaniment keys 18 are operatively connected to levers 90 which actuate the valves 22. These levers 90 are all electrically connected to the busbar 53. The busbar 53, as previously stated, is connected to the wire 54 and a cutout switch 91 is provided adjacent the busbar 53. The levers 90, when the keys 18 are manually actuated, are adapted to engage contact members 92. These contact members are respectively connected by wires 93 to the wire coils 94 of solenoids 95 mounted in the instrument 13 directly below the partition 45. A coupling block 96 is provided for the wires 93 with the accordion 12 and a coupling block 97 is provided for the wires 93 with the instrument 13. The coupling blocks 96 and 97 are constructed similarly to the coupling blocks 61 and 69 above described, the sections being freely removable to entirely disconnect the instruments 12 and 13 when desired. The solenoids 95 are constructed similarly to the solenoids 74 and have cores 98 which are connected to the bass or accompaniment valves 48, as clearly shown in Fig. 7. The opposite ends of the wire coils 94 are connected to a busbar 94 which in turn is connected by a wire 95 to the wire 76. Thus when any one of the accompaniment or bass keys 18 of the accordion 12 is manually operated a respective solenoid 95 will be operated to automatically open corresponding valves 48 in the instrument 13. The xylophone 14 has solenoids 99 mounted directly under the tone bars 50. The solenoids 99 have cores 100 which are so arranged that when the solenoids are energized the upper ends of said cores will be raised and strike the tone bars 50. One end of each of the wire coils 101 of the solenoids 99 is connected to a metallic busbar 102. This busbar 102 is connected by a wire 103 with the wire 76 to the battery 56 and includes a cut-out switch 104. The opposite ends of the wire coils 101 of the solenoids 99 are respectively connected by wires 105 to the fingers 59 on the keys 17. Coupling blocks 106 and 107 are provided respectively at the xylophone 14 and accordion 12 and these blocks are constructed similarly to the coupling blocks previously described and permit the xylophone to be entirely disconnected from the accordion 12. Considering that the switch 104 is closed, the actuation of any one of the keys 17 will cause a respective solenoid 99 to be operated and the core of said solenoid will be moved to strike and therefore vibrate the tone bar 50 under which it is directly placed.

Thus by the manual operation of the keys 17 and 18 of the accordion 12 I am enabled to effect the automatic playing of the instrument 13 and xylophone 14, and the structure is such as not to interfere with the free manipulation of the accordion 12 for the reason that all of the wires can be housed in a single cable, such as illustrated at 108 in Fig. 4 and single branches such as 109 and 110 can be respectively connected to the instrument 13 and xylophone 14. However, in Fig. 1, I have illustrated the wires as spread apart so as to clearly show the respective electric connection. Furthermore, it will be understood that the switches 55, 91 and 104 are attached directly to the accordion 12 and that they can be quickly and easily operated by the musician. For example, if the musician wishes to stop or start the automatic playing of the xylophone 14 he can do so by opening or closing the switch 130

104. Or if he desires to stop the playing of both the xylophone and instrument 13 he can do so by opening the switch 55. In the same manner if he desires to stop the playing of the basses in the instrument 13 he can do so by opening the switch 91. In Fig. 11 I have illustrated a modification of solenoid which may be used in connection with the xylophone 14 for actuating the tone bars 10 thereof and instead of actuating said tone bars from the bottom, as shown in Figs. 9 and 10 the core 111 is positioned so that when the solenoid 112 is energized the end 113 will be moved downwardly and strike 15 the tops of the tone bars 50. A spring 114 is connected to the core 111 and to an adjusting screw 115. The spring 114 serves to pull the core 111 upwardly after it has been moved downwardly to strike the tone bar 20 and after the solenoid has become deenergized.

While I have described my invention as taking a particular form, it will be understood that the various parts of my invention 25 may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. The combination of two wind operated instruments each having a melody and an accompaniment section respectively provided with valves; means for operatively connecting in combination valves of each of the accompaniment sections whereby harmonic combinations of tones are produced simultaneously in said accompaniment sections of each instrument when said means is actuated; one of said instruments having keys for operating the melody section valves

and keys for operating said combination 46 connecting means of the accompaniment valves; and automatically operative means for opening the melody section valves of the other of said instruments when the first mentioned keys are operated and for operating the combination connecting means of valves of the accompaniment section of said other instrument when said first mentioned keys are operated; substantially as described. 50 55

2. The combination of a manually operative musical instrument having a plurality of banks of keys; a busbar having elongated portions extending in zig-zag manner under the respective banks of keys; a second musical instrument having a plurality of sound producing elements; electrically operative devices for respectively actuating said latter mentioned elements to produce tones; a source of electric current; electric contacts 60 carried by said keys and normally held out of engagement with the respective elongated portions of said bus bar; means for electrically connecting said source of current with each of said electrically operative devices; and means for electrically connecting a corresponding one of said contacts respectively with each of said electrically operative devices in the second instrument whereby when each of said first keys is actuated to move its contact into engagement with said busbar the respective electrically operative device will be actuated in said second instrument; substantially as described. 65 70 75 80

In testimony whereof I have signed my name to this specification in the presence of two subscribing witnesses.

JOHN WEBER.
